[57] CLAIM

The ornamental design for a coffee bean roaster with transparent display column.

DESCRIPTION

FIG. 1 shows a perspective view of a coffee bean roaster with a transparent display column showing my new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a bottom plan view thereof; and,
FIG. 7 is a top plan view thereof.
The dotted line showing of a coffee bean heat quencher and an electric cord are for illustrative purposes only and form no part of the claimed design.
